4 Claims. (Cl. 263—29)

The bases of shaft furnaces such as blast furnaces and cupola furnaces are made of carbon or refractory bricks the sides of which are tapered and which are built up after the fashion of inverted arches that are braced by the furnace shaft or hearth masonry. Conventionally, the base is erected in layers—i.e., in the form of three or four layers of bricks placed horizontally—with the gaps between adjacent bricks in any one layer offset from the similar gaps in the layer immediately above or below. The assumption has been that the main reason for the base wearing is liquid metal penetrating into the gaps between the bricks, and so it has been thought advisable to provide a very frequent interruption of the downwardly extending gaps. A disadvantage of this kind of lining, however, is that the failure of a single brick nullifies the wedging action which keeps all the bricks together, with the result that, since the bricks forming the layer are of low density, the whole layer of bricks rises to the surface of the iron melt and is scorified.

In accordance with the present invention, the base of a shaft furnace is formed by a layer of a number of elongated refractory bricks on end, the bricks at the edge of the base being located in position and the other bricks tapering in the upward direction so that they are keyed in position against upward movement by their engagement with one another. In this single layer of tapered bricks the gaps between adjacent bricks become so long that even after considerable wear, extending possibly over a period of many years, there is little chance of penetration through the gaps to undermine the base and make it rise to the surface of the iron.

The said layer of tapered bricks forming the essential part of the base may be erected on a comparatively thin base layer of bricks the gaps between which are offset from the gaps between the upright bricks.

Preferably, the vertical construction of the upright base bricks extends as far as the lining of the furnace casing or jacket. The bottom of the jacket lining may be formed by edge bricks which are also elongated and are positioned on edge but are shorter than the rest of the bricks forming the base. There is then an interruption in the horizontal joint at the edge of the top of the base bricks.

Preferably the bricks are arranged in parallel rows and taper only along their surfaces which are adjacent bricks in the same row, the adjacent faces of one pair of adjacent bricks in each row being normal to the flat top of the base.

One example of a blast furnace base constructed in accordance with the invention is illustrated in the accompanying drawings, in which:

FIGURE 1 is a section through the hearth portion of a blast furnace taken along a vertical plane, and

FIGURE 2 is a sectional view according to line 2—2 in FIG. 1.

The blast furnace hearth portion shown in the drawing comprises in the conventional manner an outer shell of metal consisting of a partly cylindrical and partly conical side portion 1 and a base portion 2. This shell is provided with a lining of refractory material, said material consisting of bricks. These bricks are preferably made of carbon, but they may also consist of any other refractory material used heretofore in furnaces of the kind under discussion. The lining covers the base portion 2 of the shell as well as its side portion 1.

2

In the example shown in the drawing, the part of the lining covering the base portion 2 of the shell consists of a lower and rather thin layer of bricks 3 having the shape of rectangular blocks. A second layer of bricks is disposed above the bottom layer, the second layer consisting of rather tall bricks 4, 5 and 6, bricks 4 being disposed adjacent the outer shell and bricks 5 and 6 filling the space between bricks 4. The shape of bricks 5 and 6 is such that it tapers from the bottom to the top. In other words, any such brick has a bottom face of rectangular shape, a top face of rectangular shape, two opposite side faces of rectangular shape and two opposite side faces of trapezoidal shape. Thus, in one dimension, the rectangle forming the top face becomes slightly smaller than the rectangle forming the bottom face. Bricks 4 may have any suitable shape, for example that of a parallelepiped, as shown in the drawing.

It should be noted that there is a gap 7 between bricks 4 and the adjoining outer shell, this gap having a width of for example 2 to 4 inches and being filled with mortar.

While the lower layer of bricks 3 is of rather small height, the bricks 4, 5 and 6 in the upper layer may have a height of 60 to 100 inches or even more and thus are several times as high as any one of the layers used in conventional furnaces.

The part of the refractory lining covering the base portion 1 of the shell consist of two vertical layers of bricks 8 and 9, extending across part of the hearth portion of the furnace, and a single vertical layer 10 of bricks forming the upper continuation of layers 8 and 9. It will be noted that the bricks 4 are slightly less high than all the other bricks of the same layer, so that the lowermost bricks 8 of the side lining are offset against the plane formed by the entirety of the top faces of bricks 5 and 6, said plane being designated 11 in FIG. 1.

The procedure in providing the shell of a furnace with a refractory lining of the type shown in the drawing is as follows:

First, the layer of bricks 3 is placed on the bottom portion 2 of the shell in the usual manner. The surfaces of the bricks may be covered with a film of refractory sealing material, such as is obtained from a suspension of powdered carbon in water, which suspension fills the gaps between adjacent bricks. With this lower layer completed, the construction of the upper layer of tall bricks is started by placing these bricks 5 which are closest to the center on the lower layer. Starting from the center, all the further bricks 5 forming one row are then added until the row is completed, with the exception, however, of the respective bricks 4 and 6 at either end of the row. Bricks 4 are then inserted and at first pushed against the outer shell. This leaves sufficient space to introduce bricks 6, despite their tapered shape. With all the bricks of one row having been brought in position, bricks 4 are shifted inwardly to contact the adjacent bricks 6 and at the same time forming the gaps 7 which thereupon are filled with mortar.

With all the rows of bricks having been positioned in the way described, the bottom lining is completed and the side lining, consisting of brick layers 8, 9 and 10, may then be built in the usual way.

The bricks 4, 5 and 6 forming the major part of the bottom layer may also be covered with a refractory sealing film of the aforementioned nature to fill the gaps between adjacent bricks and between the upper and lower layers.

Bricks 4, 5 and 6 are so disposed on the bricks 3 of the lower layer that their joints are offset from the joints of the bricks in the lower layer, as shown in the drawing.

I claim:

1. Shaft furnace comprising an outer steel jacket and an inner refractory lining forming a hearth for the fur-

nace, said lining including a bottom and a side portion, said bottom portion comprising a relatively narrow foundation layer of bricks and a main base layer formed by a plurality of elongated bricks horizontally aligned in substantially parallel rows and superimposed on said foundation layer, said elongated bricks having a length in the vertical direction many times greater than the thickness of said foundation layer, the elongated bricks at the ends of said rows being shorter in the vertical direction than the elongated bricks elongated intermediate thereto, and said intermediate bricks being tapered upwardly in the vertical direction and being in engagement with one another so that said intermediate elongated bricks are wedged in position against upward displacement thereof.

2. Shaft furnace comprising an outer steel jacket and an inner refractory lining forming a hearth for the furnace, said lining including a bottom and a side portion, said bottom portion comprising a relatively narrow foundation layer of bricks and a relatively wide main layer formed by a plurality of elongated bricks horizontally aligned in substantially parallel rows and superimposed on said foundation layer, said elongated bricks having a length

in the vertical direction of from 60 to 100 inches, the elongated bricks at the ends of said rows being shorter in the vertical direction than the elongated bricks intermediate thereto, and said intermediate elongated bricks being tapered upwardly in the vertical direction and being in engagement with one another so that said intermediate elongated bricks are wedged in position against upward displacement thereof.

10 3. Shaft furnace according to claim 1 wherein each of the elongated bricks intermediate the end bricks of said rows has a bottom rectangular face, a top rectangular face, a pair of opposite rectangular side faces and a pair of opposite trapezoidal side faces.

15 4. A furnace according to claim 1, in which the elongated bricks are made of carbon.
